CONTROL PANEL FOR TELEVISION RECEIVER

Melvin H. Boldt, Glenview, Ill., assignor to Avco Manufacturing Corporation, Cincinnati, Ohio, a corporation of Delaware

Application September 7, 1956, Serial No. 42,866

Term of patent 14 years

(Cl. D56—4)

Fig. 1

Fig. 2

Fig. 3

Fig. 4

Fig. 1 is a perspective view of a control panel for television receiver embodying my design, taken from a frontal and lateral point of observation;

Fig. 2 is a top plan view;

Fig. 3 is a front elevational view; and

Fig. 4 is a perspective view taken from an upward and frontal point of observation, showing the control panel with the lid member open.

I claim:

The ornamental design for a control panel for television receiver, as shown.
